ATTORNEY

UNITED STATES PATENT OFFICE.

GEORGE J. MEUER, OF MILWAUKEE, WISCONSIN, ASSIGNOR TO THE CUTLER-HAMMER MFG. CO., OF MILWAUKEE, WISCONSIN, A CORPORATION OF WISCONSIN.

ELECTRIC SWITCH.

Application filed June 8, 1921. Serial No. 475,852.

This invention relates to electric switches.

While not limited thereto, the invention is particularly applicable to rotary switches for concealed mounting and has among its 5 objects to provide a simple, efficient and compact switch therefor.

Another object is to provide a rotary switch of the aforesaid character designed to minimize its dimension axially of its 10 rotary element to thereby adapt the same to relatively flat or shallow canopies and the like.

Another object is to provide a switch of the aforesaid character having an operating 15 member which may be readily removed therefrom for re-finishing, said switch being of such design as to eliminate the necessity for the usual external nut for holding the parts in assembled relation upon removal of 20 the actuating member.

Another object is to provide a switch of the character set forth comprising parts which may be readily manufactured and conveniently assembled.

25 Other objects and advantages of the invention will hereinafter appear.

The accompanying drawing illustrates a preferred embodiment of the invention which will now be described, it being understood that the switch illustrated is susceptible of various modifications without departing from the scope of the appended 30 claims.

In the drawing,

35 Figure 1 is an enlarged elevational view of the complete switch, the same being attached to a support shown in section;

Fig. 2 is a sectional view of the switch;

Fig. 3 is an interior view thereof; and

40 Fig. 4 is a detail view of one of the switch terminals.

The switch comprises stationary contacts 1 and 2 and a rotary bridging contact 3. The contact 3 is carried on a rotary insulating element 4 having four peripheral cams 5, 6, 7 and 8 which terminate in abrupt shoulders, said bridging contact 3 comprising a stamping having contact portions 9 and 10 arranged on the cam surfaces 5 and 50 7. The stationary contacts 1 and 2 have resilient extensions to bear upon the periphery of the rotary member whereby they are

snapped into and out of engagement with the contact member 3 in a well known manner upon rotation of element 4.

55 The stationary contacts which comprise reflexed leaf springs are riveted to posts 11 and 12 for support in a coplanar relation with respect to the element 4 and said posts have terminal extensions 13 and 14 respectively which are also arranged in a coplanar relation with respect to element 4 whereby the dimension of the switch axially of said element is reduced to a minimum. The terminal extensions are preferably slotted as 60 shown in Fig. 4 to receive their respective circuit wires and to permit the extremities of said extensions to be bent as shown in dotted lines for clamping the wires which are thereafter preferably soldered to 65 said extensions.

The posts 11 and 12 carrying the stationary contacts are riveted or otherwise secured to an insulating base 15 preferably of the thinnest material having the requisite 70 strength and rigidity, an insulating disc 16 being provided to cover the outer face of the base. The base and disc are provided with registering openings to receive the circuit wires 17 and 18 to be attached to the 75 contacts 1 and 2 and with registering peripheral notches 19 and 20 for a purpose hereinafter set forth.

80 The rotary element 4 carrying the bridging contact is fixed to a spindle 21 supported independently of the base 15. The spindle 21 is journaled in and solely supported by a nipple 22 carried by shell 23 forming with the base 15 an enclosing casing for the 85 switch contacts. The nipple 22 which is exteriorly threaded, serves as a supporting medium for the switch and the spindle 21 has a threaded extension 24 projecting beyond said nipple and carrying an actuating member 25 threaded thereon to bear against 90 a shoulder 26 on said spindle.

95 The shell 23 is provided with an insulating lining 27 and has lugs 28 and 29 to fit within the peripheral notches in the base and cover disc, said lugs having their extremities 100 bent to clamp said parts together. Thus the various elements are retained in assembled relation without dependence upon interlocking means on the spindle such as has

heretofore been employed, and in the structure shown the abrupt shoulders of the rotating element by engagement with the stationary contacts limit the spindle to unidirectional rotation whereby the actuating member may be readily unscrewed for removal thereof.

As shown, the switch may be attached to any desired support 30 such as a canopy by 10 projecting the nipple 22 through said support and threading onto the projecting portion of the nipple a collar or nut 31. On the other hand the nipple may if desired be provided with a plurality of threaded collars or nuts to clamp the support therebetween.

As will be understood the switch may be manufactured with short leads for the contacts to facilitate subsequent installation or 20 the switch may be directly connected to its main circuit wires and then enclosed in its casing.

What I claim as new and desire to secure by Letters Patent is:

25 1. A canopy switch for concealed mounting, comprising a bridging contact to be moved with reference to a given axis, fixed contacts to cooperate with said movable contact and located symmetrically with reference to such axis, terminal devices electrically connected with the respective fixed contacts, an insulating base to which said terminal devices are permanently secured, all parts of said fixed contacts and terminal 30 devices being located substantially within the axial extent of said movable contact, a metallic cover member secured to said insulating base, and a supporting nipple secured to said cover member and through 35 which an actuating part of said switch extends.

2. A canopy switch for concealed mounting, comprising a rotary switch mechanism having all parts of its stationary contacts and circuit terminals mounted on one side of an insulating disk, anchoring means for said contacts and terminals extending through said disk and riveted on the opposite side of the latter, an enclosing shell for 40 said switch to be permanently secured to said disk, said shell having a supporting nipple permanently connected therewith through which an actuating part of said switch extends and a second insulating disk secured to 45 the rear of the former disk to cover the parts of said anchoring means extending through the former disk, said disks having registering openings for passage therethrough of the

circuit wires to be connected interiorly to 50 said switch terminals.

3. An electric switch for concealed mounting comprising a rotary switch mechanism having all parts of its stationary and rotary contacts together with its circuit terminals of substantially equal axial dimensions and arranged in coplanar relation, an insulating disk supporting said terminals and certain of said contacts on one side thereof, a cover disk for the opposite side of the former disk, and an enclosing shell for 55 said switch having means integral therewith for clamping the same to said disks, said shell having a supporting nipple through 60 which the actuating part of said switch extends.

4. An electric switch for concealed mounting, comprising a rotary switch mechanism having all parts of its stationary and rotary contacts together with its circuit terminals of substantially equal axial dimensions and 65 arranged in a coplanar relation, an insulating disk supporting said stationary contacts and a shell having a supporting nipple through which the rotary element of said switch extends and in which said element is journaled for support independently of said disk and in centered relation with respect thereto, said shell having means comprising an inbent tongue for securing the same to 70 said disk.

5. An electric switch for concealed mounting, comprising a rotary switch mechanism having all of its cooperating contact and terminal parts of substantially equal axial dimensions and arranged to limit the switch 75 to rotation in a single direction, said switch having an actuating stem provided with an actuating member threaded thereon for removal by rotation in an opposite direction to that required for operation of said switch, an insulating support for the stationary contacts of said switch and an enclosing shell for 80 said switch having a supporting nipple within which the rotary contact element of said switch is journaled for support independently of said first mentioned support and through which said actuating stem projects, said shell and insulating support having parts comprising inbent tongues for securing the same together independently of the 85 switch and serving to retain the parts of the latter in cooperative relationship.

In witness whereof, I have hereunto subscribed my name.

GEORGE J. MEUER.
